CLAIM

(**) Term: **14 Years**

The design for a fastener for displays and store fixtures, as shown and described.

(21) Appl. No.: **29/085,756**

DESCRIPTION

(22) Filed: **Mar. 30, 1998**

The design comprises the original features of shape and ornamentation of the fastener which comprises a flat plate having a central aperture and a laterally projecting stem having angularly spaced arrays of spaced parallel fins thereon.

(51) LOC (7) Cl. **08-08**

FIG. 1 is a perspective view illustrating a first variant of the fastener embodying the design;

(52) U.S. Cl. **D8/382**

FIG. 2 is a right side view;

(58) Field of Search 403/348-349,

FIG. 3 is a top view;

403/300, 217-218; 24/585; D8/382, 387

FIG. 4 is a front view; and,

403/300, 217-218; 24/585; D8/382, 387

FIG. 5 is a left side view.
